(57) **CLAIM**

I claim, the ornamental design for an infrared heating cooker, as shown and described.

DESCRIPTION

FIG. 1 is a top and front perspective view of an infrared heating cooker, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a view showing an enlargement of the portion shown in FIG. 2; and,

FIG. 9 is a reference view showing an enlargement of the portion shown in FIG. 4.

The broken lines are shown for the purpose of depicting portions of the infrared heating cooker that form no part of the claim.
